METHOD OF KNITTING

Woldemar Heinitz, Chemnitz, Germany, assignor
to Schubert & Salzer Maschinenfabrik Aktien-
gesellschaft, Chemnitz, Germany

Application December 11, 1934, Serial No. 757,048
In Germany December 14, 1933

2 Claims. (Cl. 66—189)

The present invention relates to a method of widening fabrics on flat knitting machines, i. e. a method of widening particularly required for the manufacture of the heels of stockings.

5 Hitherto the widening of such fabrics was effected either by forming new loop wales by casting on of loops, or by transferring of loops, known as widening, for instance by transferring of loops to be sewn in the margin, or else the thread guide was, after finishing of a row of loops, moved for the pitch of two needles beyond the margin of the fabric and the thread, passing around the outer needle in a manner known for selvedge needles, was placed in front of all the needles for forming 10 a new row of loops, whereupon during the formation of the next row of loops either the last but one added selvedge needle or the last selvedge needle was not pressed and thereby received a tuck loop, whereafter further rows of loops followed.

20 Besides the disadvantage of the first mentioned method which requires rather complicated special devices and the draw-back of the second mentioned method which causes loop distortions, the fabric was enlarged or widened for two loop wales only with all these methods.

The method of widening fabrics according to the present invention allows the enlargement or widening of the fabric for the pitch of four needles 30 without requiring further special structure. This is of special importance in the manufacture of stockings in a single operation having a bending corresponding to a human's foot, as then the outer widening results quick enough with regard to the bending.

35 In the accompanying drawings Figs. 1-6 are diagrams showing the successive steps of enlarging or widening of the fabric according to the method of the invention, and Fig. 7 shows a piece 40 of fabric widened or enlarged in accordance with the method of the invention.

After the formation of the usual rows of loops *a* and *b* on the needles 11 to 28 the thread guide, coming from the right hand side of row *c* and standing outside the needle 11, outwardly passes 45 around two needles 10 and 9 as shown in Fig. 1. The thread is, in a manner known for selvedge needles, taken about the needle 9 and is then further placed in front of all needles from 10 to 28 50 for forming the row of loops *d*.

Upon the finishing of this row of loops *d*, the thread guide is in the same manner outwardly moved at the other side, i. e. at the right hand side, for the pitch of two needles, needles 29 and 55 30, the thread being laid around the needle 30 and

then further placed in front of all the needles 29 to 8 and sunk.

The foregoing operation for knitting fabric is set forth in my Patent No. 1,955,632, dated April 17, 1934 as is also the step in the method that at 5 the formation of the next row of loops the last but one added selvedge needle 10 is not pressed.

The novel feature of the present method according to the invention is the step that, when the thread guide at the right hand side is passed outwardly around the needles 29 and 30, at the same time the thread guide stop at the left hand side is moved outwardly for the pitch of two needles, i. e. the needles 8 and 7, so that the thread, as shown in Fig. 3, is not only placed in front of the needles 15 29 to 9, but also placed in front of the needles 8 and 7 and sunk, whereby the row *e* is enlarged or widened for the pitch of four needles.

After the formation of this row of loops the thread guide is, in a manner known per se, moved 20 outwardly around the needles 6 and 5 and simultaneously the thread guide stop at the opposite side of the fabric is, according to the invention, moved outwardly for the pitch of two needles, i. e. the needles 31 and 32, so that the thread 25 after having been taken about the needle 5, is placed in front of all the needles 6 to 32 and sunk, whereby the row *f* is widened or enlarged for the pitch of four needles. During the formation of this row of loops, the last but one of the previously added selvedge needles, i. e. the needle 29 30 at the right hand side, and the third last and last added selvedge needles, i. e. the needles 9 and 7 at the left hand side, are not pressed, so that, as shown in Fig. 4, the needles 7, 9 and 29 receive 35 tuck loops.

From the foregoing, it is obvious that a tuck loop is formed upon the needle 7 and the loop thereon is not knocked over into the row of loops *e*, the noose or loop formed between needles 6 and 7 cannot engage or hang itself into a loop of the preceding row of loops *e*, with the result, that the thread between needles 5 and 6 as well as between needles 6 and 7 is again stretched.

The described operation is repeated in the same manner since now, after the formation of the row of loops *f*, the thread guide at the right hand side passes outwardly around the needles 33 and 34 while simultaneously the thread guide stop at the opposite side is moved outwardly for the pitch of 45 the needles 4 and 3, so that the thread, after having been taken about the needle 34, is placed in front of the needles from 33 to 3 and sunk. Hereby the row *g* is enlarged or widened for the pitch of four needles and at the left hand side the 50 55

previously added last but one selvedge needle 8, the fourth last selvedge needle 8 and the sixth last selvedge needle 10 and at the right hand side the added last selvedge needle 32 and the third last selvedge needle 30 are not pressed, so that, as shown in Fig. 5, the needles 6, 8, 10, 30 and 32 receive tuck loops.

The operation is further repeated since now after the formation of this row of loops the thread guide at the left hand side is passed outwardly around the needles 2 and 1 and simultaneously at the right hand side the thread guide stop is moved outwardly for the pitch of the needles 35 and 36, so that in this manner now the row h is enlarged or widened for the pitch of four needles, after finishing this row, the previously added last but one selvedge needle 33, the fourth last selvedge needle 31 and the sixth last selvedge needle 29 at the right hand side and the added last selvedge needle 3, the third last selvedge needle 5 and the fifth last selvedge needle 7 at the left hand side are not pressed, whereby, as shown in Fig. 6, the needles 3, 5, 7, 29, 31 and 33 receive tuck loops.

As may be seen from Fig. 7, always each second inner loop upon each loop wale is formed as a tuck loop, so that the formation of two-needle

ladders from the newly formed pair of selvedge wales is prevented, as at least one tuck loop is present in each loop wale of the newly formed pair of loops.

What I claim is:

1. A method of enlarging or widening fabrics on flat knitting machines, in which after formation of a row of loops, a thread guide, placing thread in front of the needles, is moved for the pitch of two needles beyond the margin of the 10 fabric and simultaneously a thread guide stop at the opposite side of the fabric is moved outwardly for the pitch of two needles, so that the thread taken about the outer needle is placed in front of four more needles for forming a new row of 15 loops.

2. A method as set forth in claim 1 in which during the formation of the enlarged or widened row of loops presser motion is eliminated for a plurality of selvedge needles at both sides of the 20 row, for instance at the one side for the first, third and fifth added selvedge needle and at the other side for the second, fourth and sixth added selvedge needle, so as to form tuck loops on the non-pressed needles.
